CLAIM

The ornamental design for a face plate for a video game controller, as shown and described.

DESCRIPTION

FIG. 1 is a top, rear perspective view of a face plate for a video game controller embodying my new design, according to a first embodiment;

FIG. 2 is a top plan view thereof;

FIG. 3 is a bottom plan view thereof;

FIG. 4 is a right side elevation view thereof;

FIG. 5 is a left side elevation view thereof;

FIG. 6 is a front elevation view thereof;

FIG. 7 is a rear elevation view thereof;

FIG. 8 is a top, rear exploded perspective view thereof;

FIG. 9 is a top, rear perspective view of a face plate for a video game controller embodying my new design, according to a second embodiment;

FIG. 10 is a top plan view thereof;

FIG. 11 is a bottom plan view thereof;

FIG. 12 is a right side elevation view thereof;

FIG. 13 is a left side elevation view thereof;

FIG. 14 is a front elevation view thereof;

FIG. 15 is a rear elevation view thereof; and,

FIG. 16 is a top, rear exploded perspective view thereof.

The broken lines shown in the figures depict portions of the face plate that form no part of the claimed design.
